UNITED STATES PATENT OFFICE.

ALVOID O. MANNING, OF ORANGE, MASSACHUSETTS.

SCAFFOLDING-JACK.

SPECIFICATION forming part of Letters Patent No. 588,345, dated August 17, 1897.

Application filed May 7, 1897. Serial No. 635,484. (No model.)

To all whom it may concern:

Be it known that I, ALVOID O. MANNING, a citizen of the United States, residing at Orange, in the county of Franklin and State of Massachusetts, have invented a new and useful Improvement in Scaffolding-Jacks for Use in Connection with Ladders, of which the following is a specification.

My invention relates to a scaffold-supporting attachment or jack for use in connection with ladders; and the especial object of my invention is to provide a strong, simple, and readily-adjustable construction which is especially adapted for the use of house-painters.

To these ends my invention consists of the parts and combinations of parts, as herein-after described, and more particularly pointed out in the claims at the end of this specification.

In the accompanying drawings, Figure 1 is a view illustrating the manner in which my scaffolding-jack can be used in connection with the ladder. Figs. 2 and 3 are detail views illustrating the means which I preferably employ for locking the construction into engagement with one of the rounds of a ladder. Fig. 4 is a detail view illustrating the means which I preferably employ for adjustably connecting the two arms of my scaffolding-jack, and Fig. 5 is a detail view illustrating a foot-piece or fork for engaging a ladder-round.

In painting the exterior of houses it is now ordinarily customary to employ what are known as "swing-stages," which are supported from above and can be raised and lowered by means of suitable tackle. The use of swing-stages requires the employment of quite a number of blocks and ropes, which involve considerable labor in rigging and operating the same.

The especial object of my invention is therefore to provide a construction which may be employed in connection with a pair of ordinary ladders to support a scaffolding, and my construction is especially designed for painting the exterior of moderate-sized houses without the use of swing-stages ordinarily employed.

A scaffolding jack or support constructed

according to my invention comprises arms adjustably connected together and provided with sockets for engaging the ladder-rounds.

As shown in Fig. 1, my scaffolding-jack 55 may be secured upon an inclined ladder, so that the scaffolding can be mounted or supported on either side thereof.

As illustrated, my jack comprises two arms A and B, adjustably connected together at 60 their ends, so that the jack may be adapted for use in ladders placed at different inclinations to support a scaffold horizontally. At its inner end the arm A is provided with hooks 10 and 11 for engaging a ladder-round. A 65 locking extension or projection 12 is connected to the inner end of the piece A by means of a hinge 13.

When the arm A is to be placed in position, the locking-piece 12 is turned, as illustrated 70 by dotted lines in Fig. 2, so that the hook-pieces 10 and 11 may engage one of the rounds of the ladder. The locking-piece 12 is then turned down, as illustrated by the full lines in Fig. 2, so that the round of the ladder will 75 be locked into engagement with the hooks 10 and 11 and the hooks cannot become displaced therefrom.

The means which I employ for adjustably connecting the arms A and B are most clearly 80 illustrated in Fig. 4. As illustrated in this figure, the arm A is provided at its outer end with a notched piece or rack 14, which is bolted thereto by means of the bolts 15. The arm B is provided at its upper end with brackets 17, carrying a cross pin or bolt 18 for engaging the notched piece or rack 14. A cross-piece or retaining-strap 16 is carried by the notched piece 14 to hold the arms A and B together while the device is not in use. At 90 its lower end the arm B is provided with a foot-piece or fork 19 to engage a lower round of the ladder.

By employing two inclined ladders and two scaffolding supports or jacks of this construction I am enabled to support a scaffold at different elevations and am enabled to paint or finish the exterior of a house of moderate height much more readily than is now done by the use of ordinary swing-stages.

I am aware that changes may be made in the construction of my scaffolding-jack for

use in connection with ladders by those who are skilled in the art without departing from the scope of my invention as expressed in the claims. I do not wish, therefore, to be limited to the form which I have shown and described; but

What I do claim, and desire to secure by Letters Patent of the United States, is—

1. In a device of the class described, the combination of the connected arms A and B, the hook-pieces 10 and 11 extending from the arm A, and a single locking-section 12 arranged between the hooks 10 and 11, and pivotally connected to the arm A to lock said hooks into engagement with the round of a ladder, substantially as described.

2. In a device of the class described, the combination of a horizontal arm A, a downwardly-extending, inclined arm or prop B, and means for adjustably connecting said arms, comprising a notched piece or rack 14, a retaining piece or strip 16 arranged below said rack, pieces 17 extending up from the arm B on opposite sides of the retaining-piece 16, and a cross pin or bolt 18 carried by said

pieces for engaging the notched rack 14, substantially as described.

3. In a device of the class described, the combination of a horizontal arm A, hooks 10 and 11 extending from opposite sides of said arm, a single locking-piece 12 arranged between said hooks and pivotally connected to the arm A to lock said hooks into engagement with a ladder-round, an inclined, downwardly-extending arm or prop B, and means for adjustably connecting the arms A and B, comprising the notched rack 14, the retaining-strip 16 carried by the arm A, pieces 17 extending up from the arm B on opposite sides of the retaining-strip 16, and a cross-pin 18 secured in said pieces, substantially as described.

In testimony whereof I have hereunto set my hand in the presence of two subscribing witnesses.

ALVOID O. MANNING.
